CIRCUIT CONTROLLER

Harry E. Norviel and Leslie O. Parker, Anderson, Ind., assignors, by mesne assignments, to General Motors Corporation, Detroit, Mich., a corporation of Delaware

Application November 2, 1929, Serial No. 404,427

5 Claims. (Cl. 200—42)

This invention relates to theft preventive devices for automotive vehicles, and particularly to lock switches which, when unlocked, operate to render the ignition apparatus operative, and which, when locked, disconnect the current source from the ignition apparatus and ground a portion of the same.

It has been the practice heretofore to mount a lock switch upon the instrument board and to connect the switch with the ignition timer by a wire encased in an armor which is secured to the switch housing and timer housing in a manner such as to make it difficult electrically to disconnect the timer from the switch.

15 In the "on" position of said switch, the timer is connected with the ignition coil; and in the "off" position of said switch, the coil is disconnected from the timer, and the timer is grounded.

It is an object of this invention to improve 20 theft-preventive devices of this type in such manner as to make it still more difficult to tamper with the electrical connections in order to render the ignition operative. In the disclosed form of the present invention, the switch provides two binding posts to which both ends of the ignition primary coil are connected and connections within the switch housing whereby, when the switch is in "off" position, the coil as well as the timer is grounded.

30 Further objects and advantages of the present invention will be apparent from the following description, reference being had to the accompanying drawing wherein a preferred embodiment of one form of the present invention is clearly shown.

In the drawing:

Fig. 1 is a face view of a key controlled device substantially as indicated by the arrow 1 of Fig. 2.

40 Fig. 2 is a longitudinal sectional view through the device as illustrated by the line and arrows 2—2 of Fig. 1.

Fig. 3 is a view of the device as connected to an element essential to the operation of an automotive vehicle, in the illustrated instance a timer, the connection thereof being shown in longitudinal section.

50 Figs. 2 and 3 taken together, diagrammatically illustrate the connection of the improved device with an element essential to the operation of the automotive vehicle and illustrates the operation thereof.

Fig. 4 is a longitudinal sectional view of the switch device as indicated by the line and arrow 55 4—4 of Fig. 2.

Figs. 5, 6 and 7 are cross sectional views through the switch device substantially as indicated by the lines and arrows 5—5, 6—6 and 7—7 respectively of Fig. 2.

With particular reference to the drawing, 20 5 indicates an element essential to the operation of a motor vehicle, and in the present is illustrated as a timer comprising a cup 21 in which is secured a mounting plate 22 by screw devices 23 threaded into ears 24 of said plate. Of course 10 it is understood that the essential element may be any of the other elements necessary to the operation of a motor vehicle as the coil, distributor or even magneto, if such is to be used. Upon said plate 22 there is provided a pivot post 26 15 about which is pivoted a contact bracket 27 supporting a fixed contact 28 and adjustable thereupon by means of screw and eccentric devices 29 and 30 respectively. The post 26 insulatingly supports and pivots a circuit breaker lever 31 20 carrying a contact 32 for cooperation with the fixed contact 28, and providing a rubbing block 33 for cooperation with a cam 34 mounted upon a timer shaft 35. The breaker lever 31 is in electrical communication with a contact stud 36 25 by means of a spring 37, and is secured thereto by means of a clamping nut 38, as illustrated in Fig. 3. The stud 36 is insulatingly supported in the cup 21 and protrudes exteriorly thereof to provide a coupling member 39. The stud 39 supports an armored receiving cup 40 and is electrically connected with a lead 41 of a condenser 42, a second terminal of which is grounded to the timer cup 21 by clip 43 secured thereto.

Having nondemountable coupling engagement 35 with the stud 39, there is provided an armored coupling member consisting of a theft resisting sleeve 46 enclosing a nonconducting sleeve 47 housing a terminal 48 of an insulated electrical conductor 49, as illustrated in Fig. 3. Closing 40 the end of the sleeve 46 and securing the sleeve 47 therewithin, there is provided a spanner nut 50 disposed against a thrust washer 51 and a pair of spring locking washers 52, which provide locking engagement behind a head 53 of the coupling 45 member 39. The head 53 has electrical connection with the conductor 49 by means of the spring 54. This coupling member is such that the armored coupling member may be presented to the timer heretofore described, and forced 50 upon the coupling member 39 whereby a locking engagement will be obtained between the locking disc 52 and the said coupling member 39, and electrical connection will be made between the stud 36 and the conductor 49. 55

The armor for the conductor 49 in the present instance comprises a spirally wound tubular member 45 enclosing an interlocking spirally wound member 55 disposed about the insulation 5 of a conductor 49. The member 45 is secured to a conduit supporting coupling 56 which has a nondemountable connection with a switch casting as will presently appear.

The controller to which the foregoing apparatus is connected and by which it is operated, comprises a tubular casing 60 bifurcated at 61 and 62 to provide receiving engagement for a pair of nonconducting terminal blocks 63 and 64 as illustrated in Figs. 2, 4, 5 and 6. Each of 15 the terminal blocks 63 and 64 is substantially cylindrical in formation with a pair of diametrically opposite extensions 65 and 66, 67 and 68 respectively for reception within the bifurcations of the case 60 as will appear by reference to 20 the drawing, and provide bosses for the circuit terminal members 69, 70, 71 and 72 respectively. Each of the circuit terminal members are 25 essentially the same and comprise a tubular like headed rivet as illustrated in Fig. 5, which may be threaded to receive a terminal screw 73 to aid in securing terminals thereto. The terminal members are each passed through bores 74 of the extensions of the blocks 65, 66, 67 and 68 so that the heads 75 of said members are 30 disposed in the shank portions of leaf spring conductors within the blocks 63 and 64, and so that the tubular portions of said members extend without said blocks where they are secured by turning over the tubular portions against washers 76 as illustrated at 77. In this, each of the 35 terminal blocks and the circuit terminal members of the device are essentially the same, but each terminal block is somewhat different in structure within, as will presently appear, though each of said blocks rigidly supports a pair of leaf spring conductor members deflected toward the center of said block and normally engaging each other. The block 63 supports a pair of spring conductors 80 and 81 with their shank portions 40 secured beneath the head portion 75 of the circuit terminals 69 and 70 respectively, and may be known as ignition circuit conductors. The block 64 similarly supports a pair of spring leaf conductors 82 and 83 under the head 75 of its 45 circuit terminals 71 and 72 respectively, but here the conductors are each provided with extensions 84 and 85 respectively, for a purpose which will presently appear.

The terminal blocks thus assembled are placed 50 within the casing 60 as illustrated in Figs. 2, 5 and 6, so that the extensions 65 and 67 will be disposed in the bifurcation 62 and the extensions 66 and 68 will be disposed within the bifurcation 61 as illustrated, and so that the terminal block 64 is near the open end of the case 60. The block 63 is first placed within the bifurcations of the case 60 and the block 64 is secured to the conductor 49 by soldering the extensions 85 thereto. The extension 85 is bent inwardly 55 as illustrated in Fig. 7 and the block 64 is then placed in the bifurcation so as to present the extensions 84 and 85 adjacent the open end of the casing. With the extension 84 bent upwardly against the surface of the block 64 as 60 illustrated at 86, and the extension 85 bent inwardly and electrically connected to the conductor 49 as by soldering at 87, the coupling 56 may then be positioned within the open end of the casing 60 where it is secured by means of 65 deformations of the casing 60 being struck into

an annular groove 88 of the coupling as illustrated at 89. A sleeve member embracing the coupling 56 is then passed over the bifurcated end of the case 60 and pressed against the block 64 where it is secured by staking or spot welding it to the ends of the casing 60. The armor conductor is thus far operably associated and nondemountably connected with the casing 60 and the contact elements therewithin, and this substantially closes the outer end of the said 10 casing.

The forward end of the casing 60 is closed by a key operated controller 90 of any preferred form, but herein illustrated as a push-pull type and operably associated with means for controlling circuits through the leaf spring conductors. In main, the key operated device includes a lock barrel 91 operable by means of a key 92 to withdraw bolt 93 from an aperture 94 in the casing 60 so as to allow push-pull movement of 20 the controller 90 as defined by the limits of a stop 95 in a slot 96 of the case 60. Against the inner end of the controller 90 is disposed a contact actuator assembly including a disc 97 providing brackets 98 secured to a nonconducting 25 plate 99 carrying a movable contact 100, the actuator assembly being disposed between the flexed or free ends of the contact spring conductors 89, 81, 82 and 83. The case 60 is provided with inwardly directed squirts 101 which 30 form a seat for an annular shelf or ring 102 against which is disposed a return spring 103 that also engages the peripheral portion of the disc 97 disposed against the controller 90. This spring 103 is under sufficient compression to 35 exert a force against the ring 102 to project the controller 90 as soon as the bolt 93 is released from the aperture 94 in the case 60. In doing so, the spring 103 likewise moves the entire contact actuator assembly longitudinally between 40 the pairs of spring conductors hereinbefore described. It will be noted that the contact actuator assembly and particularly the movable contact 100 is so located that, when the controller 90 is in locked position as shown in Fig. 2, 45 the contacts 82 and 83 only will be connected; and when the controller 90 has been projected by the spring 103, the contacts 80 and 81 only will be connected.

The casing 60 is provided with a protective sleeve 105 secured about the end of the case so 50 as to cover the bolt hole 93 and the guide way 96, and that also provides a shoulder 106 which forms an abutment aiding in mounting the controller on the dash or other part of the vehicle. In mounting the unit it is customary to provide a 55 convenient aperture in a portion of the dash or instrument panel of sufficient size to receive the casing 60. The protruding end of the case 60 receives a shim 107 and is screw-threaded at 108 60 to receive a spanner nut 109, that also operates as an escutcheon plate for the lock device.

The switch thus assembled is usually connected into the ignition circuit by way of the ammeter which is connected to the terminal post 69, and 65 by way of the ignition coil, one terminal of the primary of which is connected to the terminal post 70, while the other terminal of the primary is connected to the post 72. A registering instrument, if so desired, may also be connected 70 to the terminal post 70. Other connections being properly made, including the conductor 49 and extension 85 connecting the post 72 with the elements of ignition timer 20, and the ignition timer 20 being in its respective position, 75

the device is then operatively connected into the electrical system of the automotive vehicle and will function to lockably control the ignition circuit of the vehicle, and also an auxiliary circuit 5 as that of the registering instrument.

With these connections, movement of the controller 90 to the one position, namely that illustrated in Fig. 2 will operate to open ignition circuit and registering instrument circuit through 10 the terminals 69 and 70, and to establish ground connection for the timer 20 through the connected terminal posts 71 and 72, since the conductor elements 89 and 81 will be separated by the nonconducting plate 99, and the elements 15 82 and 83 will be electrically connected through the contact 100. When the bolt 93 is withdrawn from the aperture 94 as by means of the proper key 92, the spring 103 will operate to project the controller 90 so as to withdraw the contact element 100 from between the spring contacts 82 and 83 and cause it to engage the contacts 80 and 81, whereby an electrical connection will be established between the posts 69 and 70, and the electrical communication between the posts 25 71 and 72 will be broken by reason of the end of the non-conducting plate 99 separating the leaf spring conductors 82 and 83. Under these conditions an electrical circuit will be established through the battery 120, ammeter 121, terminal posts 69 and 70, thence dividing, one portion including the registering instrument 123, while the other portion includes the primary winding 121 of the ignition coil, the terminal posts 72, the extension 85 of the leaf spring conductor 83, 30 the conductor 49 by way of elements heretofore described, to the contact point 32 of the circuit breaker lever 31 within the ignition timer 20. Thus, the ignition circuit and registering circuits are completed.

40 Depression of the controller 90, that is, pressing it inwardly to assume a position illustrated in Fig. 2, will open the ignition circuit and also the registering instrument circuit, and will subsequently close the circuit between the terminal conductors 71 and 72. Under these conditions it will be observed that the insulated conductor 49, which normally supplies electrical energy to the timer 20, is then in electrical contact with the terminal post 71 through the leaf spring conductors 82 and 83 and the movable contact 100. The terminal conductor 71 of course is grounded to the casing 60 and consequently the main structure of the vehicle, by the extension 84 that engages the coupling 56. Thence the ground connection is established with the frame of the vehicle through case 60 and the dash, or it may lead to the cup 21 through the armor 45 and other obvious connections. It will be observed that the ignition coil 122 as well as the timer 20 is grounded upon the frame since one terminal of the coil is connected at 72. Thus, when the ignition is turned off both the timer 20 and the coil are cut out of an active or live circuit in the vehicle, and both grounded to the frame of the vehicle making it doubly difficult for the unauthorized person to eliminate the theft protection afforded by this device.

While the form of embodiment of the present invention as herein disclosed, constitutes a preferred form, it is to be understood that other forms might be adopted, all coming within the scope of the claims which follow.

What is claimed is as follows:

1. In a theft preventing device for automotive vehicles, a lock switch controller comprising in

combination, a casing, a plurality of contact assemblies supported within the casing, a single movable contact element optionally engageable with all of the conductive elements of the contact assemblies, a lock plug for actuating the movable contact into one circuit closing position, a spring for resisting actuation of the lock plug and for returning the movable contact to a second circuit closing position, and means forming a spring seat within the casing comprising inwardly directed 10 squirts of the casing, and a ring disposed against said squirts to receive one end of said spring. 5

2. In a theft-preventing device for automotive vehicles, a lock switch controller comprising in combination, a tubular casing, a plurality of contact assemblies supported within the casing at one end thereof, a lock plug axially movable along and located in the other end of said tubular casing, a movable contact assembly enclosed by the casing and providing a U-shaped contact element 20 for bridging pairs of contacts provided by each of the contact assemblies, a spring within the casing forcing the movable contact assembly to follow the lock plug and means forming a spring seat for one end of the spring, said means including portions of the tubular casing intermediate the lock plug and contact assemblies struck inwardly to form abutments for one end of said spring. 25

3. In a theft preventing device for automotive vehicles, a lock switch controller comprising in combination, a tubular casing having a bifurcated end, a plurality of ring-like bodies within the casing and having extensions located in the case bifurcations, a contact supported within the 30 casing at each of the ring extensions, a movable contact assembly comprising a single bridging contact, a lock plug and spring for actuating the movable contact into either of a plurality of positions in each of which the contacts of only one 35 of the ring-like bodies are bridged, and means including a part of the tubular casing providing a seat for the said actuating spring.

4. In a circuit controller for an ignition device, the combination of, a tubular casing having one 45 end bifurcated to provide parallel tongues, a controller mounted for limited movement in the other end of the casing, a spring urged contact assembly for actuation by the controller and having a contact for movement along the axis of the bifurcated 50 end of the casing, a pair of ring like terminal supports in end to end relation within the bifurcated end having projections extending between the casing tongues, flexible contact blades secured to the supports at the projections and bent inwardly 55 to engage said contact assembly, and means secured to the bifurcated end of the casing for pressing the rings together and toward the bottom of the bifurcation for closing off the bifurcated end of the casing, said contact assembly being movable 60 between the contact blades, and adapted to bridge the contact blades of but one ring-like member at a time.

5. In a circuit controller for an ignition device, the combination of, a tubular casing having one 65 end bifurcated to provide parallel tongues, a controller mounted for limited movement in the other end of the casing, a spring urged contact assembly for actuation by the controller and having a contact for movement along the axis of the bifurcated 70 end of the casing, ring like terminal supports within the bifurcated end having projections extending between the casing tongues and disposed about the contact assembly, conductive elements carried by the projections and accessible 75

- from without the casing, said conductive elements having flexible portions within the casing engageable with the movable contact assembly, two opposite ones of the flexible portions being in closed circuit in one position of the controller, and two others of which are in closed circuit only in another position of the controller, and means
- 5

engaging the tongues of the bifurcated case end for preventing circuit closure between any of the elements enclosed within the casing except by the spring urged controller.
